UNITED STATES PATENT OFFICE.

THOMAS A. HARGRAVE, OF GALVESTON, TEXAS.

DRYING AND STRETCHING FRAME.

No. 919,007.

Specification of Letters Patent.

Patented April 20, 1909.

Application filed August 18, 1908. Serial No. 449,173.

To all whom it may concern:

Be it known that I, THOMAS A. HARGRAVE, a citizen of the United States, residing at Galveston, in the county of Galveston and 5 State of Texas, have invented new and useful Improvements in Drying and Stretching Frames, of which the following is a specification.

This invention relates to a frame for drying and stretching lace curtains and other fabrics, the object of the invention being to provide a frame of this character which can be readily and conveniently adjusted to receive curtains or fabrics of different dimensions and to stretch the same to the desired tension, which is adapted to permit of the ready and convenient application and removal of the fabric to be dried and stretched, and which is also adapted to be conveniently 10 set up for use and taken down for package or storage in close compass.

The invention consists of the features of construction, combination and arrangement of parts hereinafter fully described and 15 claimed, reference being had to the accompanying drawing, in which:—

Figure 1 is a perspective view of a drying and stretching frame embodying my invention and as set up for use. Fig. 2 is a detail 20 longitudinal section on an enlarged scale through a portion of the same.

The device comprises four corner posts or standards 1 carrying at their upper ends heads 2, which are threaded or otherwise 25 detachably mounted upon the standards, but may be suitably fixed thereto. Each of these heads is formed with a pair of transverse openings 3 and 4 extending horizontally therethrough and arranged at right 30 angles to each other, as shown. The openings 3 are adapted to receive the ends of the side rods or bars 5, and which are adapted to be adjustably secured therein by thumb screws 6, while the openings 4 are adapted to 35 receive the ends of end rods or bars 7 which are adapted to be adjustably secured therein by thumb screws 8.

The rods or bars 5 and 7 form a rectangular frame to receive and support the curtain or 40 other article of fabric to be dried and stretched, and each of these rods or bars carries a series of spaced hooks 9 to engage and support the adjacent edge of the fabric. These hooks may be arranged at any suitable 45 distance apart as occasion may require, and

may be made of any suitable material. Each hook is suspended from and slidably mounted upon the rod by a ring or collar 10, thus permitting the same to be adjusted. Stop devices 11 in the form of annular coil 60 springs are arranged upon each rod beyond the terminal hooks and between the same and the standards, such stops serving to prevent the hooks from slipping off the rods when the latter are disconnected from the 65 standards.

The frame may be adjusted as to width by the sliding engagement of the rod 7 with the corner posts or standards, and it may be adjusted as to length by the sliding engagement of the rods 5 with said posts or standards, so that its size may be varied within reasonable limits to receive and support curtains or other fabrics of different sizes. In order to enable the length of the frame to 70 be additionally increased, as well as to enable the parts to be taken down for packing in close compass, each rod 5 is preferably composed of two sections 5^a and 5^b, which are connected at their meeting ends by a coupling sleeve 12. The end of the rod section 5^a is threaded to fit within one end of the sleeve, which is threaded for its reception, while the end of the rod section 5^b is slidably fitted in the opposite end of the sleeve and is adapted 75 to be secured therein by a binding screw 13. By this construction the rods 5 may be adjusted as to length to additionally extend the frame or to stretch the curtain or fabric to a desired tension. The posts or standards 1 may be provided at their lower ends with base pieces or feet 14 to form a firm and steady support for the erected frame.

In operation, the frame is set up in the manner shown in Fig. 1 and the bars or rods 95 adjusted to make the frame of slightly less dimensions than the curtain to be dried and stretched. The hooks are then engaged with the edges of the curtain to secure the same to the frame, and then the parts are adjusted 100 to increase the dimensions of the frame to a sufficient extent to make the curtain taut. After use the parts of the device may be disassembled in an obvious manner and the sections of the rods 5 uncoupled, thus enabling 105 the parts to be placed in close compass for storage or transportation. The spring stop bands or rings 11 preferably grip the rods with sufficient friction to prevent displacement thereof, but may be by the exercise of 110

slight force pulled off the rods to enable the hooks to be disengaged therefrom whenever desired.

Having thus fully described the invention, 5 what is claimed as new is:—

A curtain drier and stretcher embodying a rectangular frame comprising corner posts or standards, side and end rods slidably engaging said posts or standards for varying 10 the dimensions of the frame, means for securing the parts in adjusted position, curtain

engaging devices slidably engaging the rods, and resilient bands slidably fitted on each rod beyond the terminal supporting devices and operating as stops to retain said devices upon 15 the rod.

In testimony whereof I affix my signature in presence of two witnesses.

THOS. A. HARGRAVE.
